CAR DOOR

Argyle Campbell, Chicago, and George B. Willard, Western Springs, Ill., assignors to Enterprise Railway Equipment Company, Chicago, Ill., a corporation of Illinois

Application June 9, 1933, Serial No. 675,078

7 Claims. (Cl. 189—46)

Our invention relates to improvements in car doors for railway cars.

An object of our invention is to provide a door structure incorporating a door supporting track 5 runway and door supporting anti-friction means in combination with a weather and dust-proof seal at the lower margin of the door.

Another object of the invention is to provide a door and anti-friction door supporting means 10 which may be applied in a restricted space and still maintain adequate strength to prevent bending and warping of the door.

A more specific object of our invention is to combine anti-friction door supporting elements 15 in the door structure with the structural elements of the door and car framing in such a manner as to strengthen the door.

Further objects of the invention will appear 20 from the drawings, description and claims appended hereto.

Referring to the drawings:

Figure 1 shows a longitudinal side elevational view of a part of a railway box car showing an embodiment of our invention.

Figure 2 is an enlarged sectional plan view taken through the lower portion of the door and on a line corresponding to line 2—2 of Figure 1.

Figure 3 is an enlarged sectional plan view taken through the rear portion of the door and on a line corresponding to line 3—3 of Figure 1.

Figure 4 is a vertical sectional view on an enlarged scale taken through the lower portion of the door and car structure, on a line 4—4 of Figure 1.

Figure 5 is a vertical sectional view on an enlarged scale taken on a line 5—5 of Figure 1.

Figure 6 is a longitudinal side elevational view of a portion of a railway car showing a side door and related car construction illustrating a modified form of our invention.

Figure 7 is an enlarged vertical sectional view taken through the lower portion of the door and car structure and on a line 7—7 of Figure 6.

Figure 8 is an enlarged vertical sectional view taken through the lower portion of the door on a line 8—8 of Figure 6.

Figure 9 is an enlarged sectional plan view taken through the outer portion of the door on a line 9—9 of Figure 6.

Figure 10 is an enlarged sectional plan view taken through the rear portion of the door on a line 10—10 of Figure 6.

Figure 11 is a longitudinal elevational view of 55 the lower portion of a side door and related car

structure showing another modified form of our invention.

Figure 12 is an enlarged vertical sectional view taken through the lower portion of the door and associated structure on a line 12—12 of Figure 11.

Figure 13 is an enlarged plan view taken through the lower portion of the door on a line 13—13 of Figure 11.

Referring first to the construction illustrated in Figures 1 to 5, inclusive:

is preferably formed of an angle having one of its flanges 29 transversely disposed and modified at its end as indicated at 30 to provide a U-shaped portion adapted to engage in wedging relation 5 rearwardly of flange 18 of the rear door post structure. The said members 23 and 24 define substantially the thickness of the door. The panelling 26 terminates an appreciable distance 10 above the lower margin of the door and the lower portion of the door is completed by a panel and the latter is preferably formed of metal of greater thickness than the upper panel 26, said panel 31 includes an edge portion 32 which overlaps and is united with the main panelling 26 along a horizontal 15 line of rivets 33; said panel 31, below the joint, is offset inwardly as indicated at 34 and thence downwardly as indicated at 35, thereby presenting a facing plate portion lying in the inner plane of the door; said facing portion 35, 20 as will be noted by reference to Figure 4, extends for an appreciable distance above the threshold plate and adjacent the runway surface is deflected outwardly to present a substantial horizontal portion as indicated at 36 which lies substantially 25 in the plane of the runway 19.

Beyond the depending flange 21 of the track, the panel 31 is again deflected downwardly to present a vertical section 37 and inwardly at 38 and thence upwardly at 39. The walls 37, 38 and 39 form a hook-shaped section at the lower extremity of the door which extends around the depending flange 21 of the track for substantially the entire length of the door. At each end of the door a connection is effected between the bottom member 31 and the vertical marginal members by means of brackets 40.

It will be noted that the shape of the member 31 provides for exceptional strength in transverse, horizontal and vertical directions as the 40 flanges 32, 34 and 35 provide in effect a Z-shaped member at the location where the door is most likely to be damaged due to contact with shifting of lading in the car, or other external causes. In like manner the walls 35, 36 and 37 cooperate 45 to form a Z-shaped section adjacent the supporting track and said beams in cooperation with the hook-shaped lower portion at the bottom of the door by reason of cooperating engagement between said hook-shaped portion of the door and the flange of the track effectively protects the door against warping.

Adjacent each end of the door the lower flange is provided with an opening 41 and in alignment with each said opening a housing 42 is disposed 55 in the channel-shaped offset provided by the walls 34, 35 and 36. Each said housing includes a hollow section having a pair of walls 43 and 44, spaced from each other and united transversely of the door by vertical walls 45-45 and an upper 60 wall 46, said last named wall 46 being adapted to bear against the wall 34 of the channel shaped offset. The housing 42 which is preferably formed of a casting includes wall portions at the top and bottom as indicated at 47 and 48, said 65 walls being adapted to overlie the edge wall portions 32 and 37 respectively of the beam member 31 and be riveted thereto by means of rivets 49.

In order to permit use of full headed rivets on 70 the inner side of wall 37, for attachment of the door roller housing brackets, said wall is provided with bulged out portions 50 for the purpose of providing a chambered portion to accommodate rivet heads 51 and maintain the latter free of and beyond the depending flange 21. The walls 75 43 and 44 form supporting means for a pivot pin

52 on which is mounted a roller 53. The portion of the outer wall adapted to receive pivot pin 52 is extended lengthwise of the pin as indicated at 53, and said pin is retained against lengthwise displacement by a rivet member 54.

The outer wall 44 of the housings are reinforced in a vertical direction by ribbing means 55 thereby utilizing the brackets as strengthening means intermediate the upper and lower portions of the channel shaped offset of member 31. The body 10 of the panel 26 above the lower panel 31 is reinforced by means of suitable bracing members 56 which have their lower ends secured to the upper portions of panel 31.

In the modifications shown in Figures 6 to 10 inclusive: 100 indicates the usual side wall of a box car; 101 the floor boards; 102 the car side sill; and 103 the door posts, the latter being respectively disposed at the front and rear ends of the door opening. The door is indicated at D, said door being adapted to have sliding movement on a track E.

The track E is preferably in the form of a Z-bar having its web 104 horizontally disposed and extending outwardly beyond the face of the door opening to provide a runway extending for an appreciable distance outwardly beyond the face of the wall incorporating the door opening. The inner flange 105 of the track is riveted to the side sill and said track at its outer end is provided with a depending flange 106.

The door D includes front and rear marginal members 107 and 108, each said member being of appreciable thickness and having flanges 109 overlying and secured to door metallic panelling 35 110 and 111, said door panelling is reinforced by a series of braces 112, 113, 114 and 115; the lower panel 111 is preferably formed of greater thickness than the upper panel 110 and said respective panels are united along a horizontal line of rivets 40 116. The panel 111 below the joint 116 is deflected outwardly at 117 and extended downwardly as indicated at 118, to extend below the depending flange 106 of the track panel and said panel at its lower extremity is bent inwardly beneath the track as at 119 and thence upwardly at 120 to present a hook-shaped portion extending around the said depending flange 106 of the track.

Extended lengthwise of the door, on the inner side adjacent the floor of the car, there is 50 provided a Z-shaped member 121 which is attached by means of one of its flanges 122 to both the panels 110 and 111 by rivets 116, said Z-shaped member has its web 123 extending transversely of the door and is disposed with its other flange 124 55 lying adjacent to the floor to provide a facing plate for cooperation with the face of the car wall adjacent the door opening. Intermediate the walls 124 and 118, there are accommodated door supporting roller housings 125, each said housing includes a hollow box shaped portion having inner and outer walls indicated at 126 and 127 respectively; transverse walls 128-128 and an upper wall 129; said walls 127, 128 and 129 provide a hollow casing adapted to bear against wall 123 of the Z-shaped member. On each side of the box shaped portion the housings are provided with walls 130 which are riveted to the wall 118 of the bottom panel 111.

The walls 125 and 126 support a pin 131 on 70 which is mounted an anti-friction roller 132, said roller being adapted to have cooperating engagement with the track for supporting the door. The door supporting rollers 132 are located adjacent the ends of the doors and intermediate said 75

supporting means there are disposed a plurality of brackets 133 which are riveted to the face of the plate 111 and serve as spacing and supporting means for the intermediate portion of the Z-shaped member 121.

In the modification shown in Figures 11 to 13 inclusive, our improved structure is shown in connection with anti-friction ball bearing supporting means.

10 In said embodiment of our invention, 200 indicates the side wall of the car, 201 the floor boards, 202 the car side sill and 203 the door posts. The door is indicated at F and the door supporting track at G. The track is in the form of a bulb angle having a web 204 horizontally disposed and presenting a runway for the door; said track has the flange 205 overlying the car side sill and riveted thereto by rivets 206 and at the outer edge the trackway is provided with a depending flange 207. The door F includes front and rear marginal members 208 and 209, and the body of the door intermediate the vertical margins consists of metallic panelling 210 riveted to the framing members and suitably reinforced on its inner side by members 211. The lower margin of the door is reinforced by plate member 212 having its upper edge portion 213 disposed in overlapping relation with panelling 210 and riveted thereto by row of rivets 214, said member below the edge portion is deflected downwardly and outwardly as indicated at 215, thence downwardly as at 216, inwardly as at 217 and upwardly as at 218 to present a hook-shaped portion extending around the depending flange 207 of the track.

35 On the inner side of the door there is disposed a beam member 219, said member having a vertical wall 220 secured to member 212 and to the panelling 210 by means of the row of rivets 214, said member 220 is provided with a horizontal portion 221 and a vertical portion 222, the latter being disposed in the inner plane of the door; said member 219 by reason of the Z-shape formation imparted by the flanges 220, 221 and 222 serves to materially strengthen the door against bending. Interposed between the panel 222 and 216 there is provided movable anti-friction door supporting means 223 consisting of a carriage member 224 having a pair of anti-friction balls 225 at each end thereof, said anti-friction means are adapted to bear on the runway of the track and on the underside of wall 221 of the member 219. The wall 221 is extended to the opposite sides of wall 220 as indicated at 226, for the purpose of extending the bearing surfaces above the anti-friction means.

50 It will be observed that the various modifications of our invention provided for the application of anti-friction door supporting means in locations where they are protected against damage from the interior and exterior of the car, and the disposition of said supporting means in the body of the door permits of the maximum strength being built into the door, inasmuch as the inner and outer walls of the door provide a beam effect to stiffen the door and counteract bending tendencies.

55 Furthermore, the parts are of simple construction such as may be readily manufactured and assembled.

70 While we have shown and described preferred embodiments of our invention the same are merely illustrative and we contemplate all changes that come within the scope of the claims appended hereto.

75 What we claim is:—

1. The combination with a car body having a door opening and a sliding door for said opening; of a track located at the lower margin of said opening, said track presenting a substantially horizontal runway and a depending flange; said door at its lower edge being formed with an angularly bent plate portion presenting horizontal and vertical wall sections lying above the runway and outwardly of the depending wall of the track respectively; said horizontal wall section of the door having openings therein; anti-friction door supporting means disposed outwardly of the plate and extending through the openings for supporting engagement with the track; said depending wall section of the door beyond the flange, being beneath and rearwardly of said depending flange of the track.

2. In a railway car, the combination with a supporting track having a horizontal runway and a depending flange adjacent the outer edge of said runway; of a door mounted for sliding movement on said runway, said door having a panel adjacent its lower portion formed with edge wall portions extending lengthwise of the door in a plane parallel with the main plane of the door, said panel intermediate the edge portions being offset inwardly in the plane of the supporting track runway; said offset having openings formed in the lower portion thereof; door roller supporting housings disposed in the offset and secured to the respective edge portions of the panel member; and a roller pivotally mounted on each housing, each said roller being disposed in alignment with and extended through one of the openings in the offset.

3. In a metal door of the sliding type formed of sheet metal panelling extending the width of the door; a panel at the lower portion of the door, said panel being inwardly offset to substantially channel-shape with a lower wall extending substantially horizontally and having openings formed in said horizontal wall; and door supporting means located in said channel shaped offset, said door supporting means including rollers adapted to extend through the openings in the lower horizontal wall and bear on the supporting track.

4. The combination with a car having an opening and a door supporting track located at the lower margin of the opening, said track having a horizontal runway portion and a depending flange at its outer edge; of a door mounted for sliding movement on said runway, said door having adjacent its lower edge a plate member having an inwardly offset portion providing a horizontal portion extending above the runway of the track and having openings formed therein; said plate member being extended downwardly along the outer face of the depending flange and bent to provide a hook-like extremity for the lower edge of the door, for enclosing the depending flange of the track; and door supporting means for the door disposed outwardly of the said offset portion; said means including rollers adapted to project downwardly through the openings formed in the horizontal portion of the plate member.

5. In a sliding door structure for railway cars, the combination with a door opening formed in the wall of a car; of a track at the lower portion of the door opening, said track having a depending flange; a door of appreciable thickness adapted to slide along the side of the car wall on said track to close said opening, said door having the main body portion formed of sheet metal pan-

elling disposed in the outer plane of the door, said door at its lower margin having a panel section dished inwardly from the outer plane of the door to present a vertical wall lying in the inner plane of the door, said vertical wall section above the runway being deflected outwardly and downwardly to present a section lying in the outer plane of the door; said outer section being extended downwardly and bent to present a 10 loop portion extending around the depending flange of the track.

6. In a railway car door of the type adapted to be mounted for sliding movement along a supporting track; said door being of appreciable thickness; a reinforcement for the lower portion of the door, said reinforcement including a panel formed with edge portions extending lengthwise of and in the outer plane of the door; said panel intermediate the edge portions being offset inwardly from the outer plane of the door; openings formed in the lower portion of the offset; door roller housings disposed in the offset, each said housing having a wall portion overlying and riveted to the lower edge portion; said edge portion being formed with an outwardly bulged portion to accommodate rivet heads; and rollers carried by the said housings to extend through the openings in the offset wall.

7. In a railway car door of the type adapted to be mounted for sliding movement along a runway, said door being of appreciable thickness; a panel for the lower margin of the door, said panel having edge wall sections extending lengthwise of the door in substantially the outer plane of the door, said panel intermediate the edge wall sections being offset inwardly to provide a channel shape presenting a web disposed in substantially the inner plane of the door; a plurality of openings formed in the lower portion of the offsets; bulged-out portions in the lower edge wall section adapted to provide recesses in the wall in alignment with each said opening; door roller housings disposed in the channel shaped offset and each formed with an attaching wall overlying the bulged-out portion of the lower edge wall section; securing means for securing the attaching wall of the housings to the lower edge wall section, said securing means having a headed portion lying in the recess; and a roller pivotally mounted on each housing, each said roller being disposed in alignment with and extended through one of the openings in the offset for cooperating with the track. 25

ARGYLE CAMPBELL.
GEO. B. WILLARD.
